UNITED STATES PATENT OFFICE

RALPH A. OSTBURG, JR., OF WINCHESTER, MASSACHUSETTS

PRACTICE KEYBOARD

Application filed July 30, 1930. Serial No. 471,610.

This invention relates to a practice key board and more particularly to such a device for use in training beginners in rhythm and in the fundamental finger movements of piano playing.

An object of the invention is to provide a simple, inexpensive device such that each member of a class or group receiving instruction may be provided with one.

Another object of the invention is to give the keys a tension approximating as nearly as possible the tension of the keys of a tuned piano, and to allow the same time interval for the return of the keys to normal position after being depressed, as is the case in a tuned piano.

Still another object of the device is to overcome the dull, flat sound of a key striking an ordinary base, by providing an impact member having a predetermined resonance.

Other objects and novel features of the invention will be pointed out and clearly defined in the claims at the close of this specification.

In the drawings:

Fig. 1 is a perspective view of the device, Fig. 2 is a longitudinal section taken on the line 2—2 of Fig. 3, and

Fig. 3 is a transverse section taken on the line 3—3 of Fig. 2.

Before explaining in detail the present invention, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

As illustrated herein the key board is contained within a frame comprising the front cross member 10, the sides 11, the back cross member 12, and the cover 13, hinged to the back cross member. In addition there is a

guide board 14 at the rear of the front cross member 10, and a stop board 15 extending across the top of the frame and abutting the cover 13 when the latter is in closed position, the purpose of which will be hereinafter described. The key board is comprised by the full-tone or white keys 16, and the half-tone or flat keys 17, exactly as in the keyboard of a piano, except that in the embodiment of the invention described herein only two and a half octaves are provided. The length of the key board and the number of octaves included may of course be varied as may seem desirable.

A shaft or pivot rod 18 is suspended between the side members 11, at a point between the center and the rear of the device, and the keys 16 and 17 are threaded thereon or otherwise mounted so as to be capable of revolving about said shaft as an axis. Since the keys are pivoted at a point adjacent their rear ends it will be well understood that unless some tensioning means is provided the front ends of the keys will drop down whereas normally the keys should maintain a horizontal position. Tensioning means may be provided in any suitable way, but applicant prefers to use for this purpose elastic bands of a predetermined and uniform size and quality, joining the rear end of each key to the back cross member 12. The elastic bands may be simply slipped over pins 19 provided for this purpose along the back cross member 12, and on the rear end of each of the keys 16 and 17, and the tension may be easily adjusted by making one or more turns of the elastic around one of said pins. Springs or other tensioning means may be provided in place of the elastic bands, which have been chosen for the purpose of economy. By using elastic bands of uniform size and quality, the resistance of the keys of a tuned piano may be approximated.

As shown in Fig. 3 each of the white keys 16 is provided at its front end with a stop pin 20 which travels in a corresponding vertical slot or guide 21, provided in the guide board 14. When the keys 16 are in their normal position the pins 20 will be at the upper ends of the slots 14, which thus serve to limit

the upward movement of these keys, and to overcome any tendency which the elastic bands might have to raise them beyond their normal position.

5. The half-tone or black keys 17 are similarly limited in their upward movement by the stop board 15, which is provided with an interlining 22 of some soft material such as felt to render the action noiseless.

10. Extending longitudinally across the device below the white and black keys respectively are two sounding boards 23 and 24 against which the keys strike when depressed. I have found by repeated experiment that by 15 providing holes 25, through the boards 23 and 24, they will give a resonant sound when struck, instead of a dull, flat sound, which is the case when the keys strike the surface of a solid impact member. I have also found 20 that by making the holes 25 of a definite diameter and spacing them at regular predetermined distances I can obtain the resonance of middle A of a piano. This is a highly desirable feature since it gives a 25 musical note to the impact of the keys, greatly increasing the value of the device as a means of teaching rhythm and adds greatly to the enjoyment of the pupils.

I claim:

30. 1. A practice key-board comprising in combination a frame, a number of keys pivotally mounted in said frame so that the front ends of said keys may be depressed to simulate the action of playing a piano, means for 35 raising said keys to their normal position, and a member against which said keys strike when depressed, said member being adapted to give a predetermined resonance to the sound of the impact of said keys.

40. 2. A practice key-board comprising in combination a frame, a number of keys mounted in said frame so that they may be depressed to simulate the action of playing a piano, means for returning said keys to normal position after being depressed, and a sounding 45 board for said key-board against which said keys strike when depressed, said sounding board having a number of air spaces formed therein to give a predetermined resonance to the sound of the impact of said keys.

50. 3. A practice key-board comprising in combination, a number of keys mounted in a frame so that they may be made to simulate the action of the keys of a piano, and a sounding board for said key-board comprising a 55 rectangular member extending the full length of said device and having a number of air spaces extending through said member laterally, said air spaces being distributed so as to give a predetermined resonance to said board.

60. 4. A practice key-board comprising in combination a frame, a pivot rod, a number of keys rotatably mounted on said pivot rod, elastic means joining the rear end of each of

said keys to said frame, and a sounding board for said key-board against which said keys strike when depressed, said sound board having a number of air spaces extending therethrough, the size and distribution of 70 said air spaces being such that said board when struck by one of said keys will give a predetermined note.

5. A practice key-board comprising in combination a frame, a pivot rod supported within said frame, a number of full tone and a number of half tone keys mounted on said pivot rod arranged as in the key-board of a piano, a sounding board for said key-board against which each of said keys strikes when depressed, means exerting a tension on the rear end of said keys to return them to normal position when depressed, said means approximating the tension exerted on the keys of a tuned piano, and separate stop means 80 limiting the upward or return movement of each of said keys.

6. A practice key-board comprising a sounding board having a predetermined resonance and a number of keys rotatably mounted above said sounding board and adapted when depressed to strike against said sounding board to produce a musical note.

7. A practice key-board comprising a number of keys rotatably mounted on a horizontal axis, a resonant member against which said keys normally contact when rotated forwardly, and means for gradually and evenly returning said keys to raised position above said resonant member, said means comprising elastic connections joining the rear ends of the respective keys to the frame of said key-board, said elastic connections being adapted when said keys are rotated forwardly to 100 stretch evenly throughout their length.

8. In a practice key-board having a number of keys mounted so that the front end may be depressed, the means for giving instruction in rhythm comprising a resonant member against which said keys are adapted to strike when depressed, said member having a number of apertures extending therethrough arranged in parallel relation and spaced apart a predetermined distance.

9. A practice key-board comprising a number of pivotally mounted keys and a sounding board underlying said keys and adapted to give to the impact of each key a predetermined resonance.

10. A practice key-board comprising a number of pivotally mounted keys and a sounding board underlying said keys and adapted to give to the impact of each key the resonance of middle A of a piano.

11. A practice key-board comprising a number of pivotally mounted keys and a sounding board against which said keys strike when depressed, said sounding board having a number of holes therethrough

spaced so that when struck by any of the keys it will give a resonant sound approximating that of middle A.

12. A practice key-board comprising a frame, a number of keys rotatably supported within said frame adjacent their rear ends, connections between the rear end of said keys and said frame, said connections being adapted to stretch evenly throughout their length and to contract evenly and gently and having sufficient tension to raise said keys when they are depressed, and a sounding board for said key-board comprising a rectangular member against which said keys are adapted to strike when fully depressed in the normal use of the device, said member having a number of parallel apertures extending through said member laterally.

13. A practice key-board comprising a frame, a number of full-tone and a number of half-tone keys pivotally mounted adjacent their rear ends in said frame, and a plurality of sounding boards against which said full-tone keys and said half-tone keys respectively are adapted to strike, each of said sounding boards having a number of apertures of predetermined diameter extending therethrough in parallel relation.

14. A practice key-board comprising a frame, a number of full-tone and a number of half-tone keys pivotally mounted adjacent their rear ends in said frame, and a plurality of sounding boards against which said full-tone keys and said half-tone keys respectively are adapted to strike, each of said sounding boards having a number of apertures of predetermined diameter extending therethrough in parallel relation, and connections between the upper surface of the rear end of each of said keys and the said frame, said connections having sufficient tension to rotate said keys into normal raised position after they have been depressed, said connections being evenly stretchable throughout their entire length and capable of raising said keys with a movement approximating that given to the keys of a tuned piano by the counterweights carried at the rear ends of said keys.

In testimony whereof I affix my signature.

50 RALPH A. OSTBURG, JR.
